UNITED STATES PATENT OFFICE.

MAURICE BOXER, OF SAN FRANCISCO, CALIFORNIA.

HAIR CURLER.

Application filed August 31, 1925. Serial No. 53,738.

My invention relates to curling devices for use in curling and waving hair, and particularly to a device of this character, for giving a so-called permanent wave to the hair.

One of the objects of the invention is the provision of a hair curling device which lends itself to easy handling and quick application to the hair. Another object of the invention is the provision of a hair curling device which may be worked close to the scalp and which does not permit the slipping off of the first turn or coil of hair after the hair has been applied to it.

My invention possesses other objects and features of advantage some of which with the foregoing will be set forth in the following description of the preferred form of my invention which is illustrated in the drawings accompanying and forming part of the specification. It is to be understood that I do not limit myself to the showing made by said drawings and description, as I may adopt variations of the preferred form within the scope of my invention as set forth in the claims.

Referring to the drawings, Fig. 1 is an elevation of my complete hair curling and waving device, showing the same applied to a strand of hair. Fig. 2 is a perspective view of my device, as actually applied to a strand of hair, and before the heating housing is applied to it. Fig. 3 is an elevation of three of the parts of my device, showing them separated but in the relative positions in which they go together. Fig. 4 is a transverse sectional view, on an enlarged scale the plane of section being indicated by the line 4—4 of Fig. 3.

In terms of broad inclusion, my invention comprises a frame on which the hair may be wound. The whole of the hair is divided into conveniently sized strands, each of which is wound about the frame. Means are provided for preventing the slipping off of the first turns of the hair strand, from the end of the frame; and the proportions and arrangements are such that the frame may be worked close to the scalp so that the curl or wave applied to the hair begins closely adjacent to the head. The frame is made of several parts, so that it may be expanded to stretch the hair very slightly after the hair is applied to it. After the hair strand has been wound about the frame, and the frame expanded, the frame with the hair

thereon, is inserted within a heating housing. The heating of the stretched hair wound about the frame, fixes the curl or wave, so as to give the so-called permanent wave to the hair. Upon the release of the expanding means, the frame contracts to permit the ready disengagement of the hair from it. In practice it is customary to use a considerable number of my devices at one time, one for each strand of hair to be curled or waved.

In greater detail, my invention comprises a frame formed of tubular sections 2 and 3. These sections are preferably formed in suitable dies, and are arranged to fit together as shown in Figures 2 and 3, to form normally a closed tube. It is desired to have these parts of the frame resiliently retained in the position shown; and in Figure 3, I show one method of accomplishing this. In stamping out the frame parts, beads 4 are formed on each part following the line of a thread, so that a spring 6 may be threaded over the ends of the juxtaposed parts to hold them resiliently together, and yet permit them small separating movement.

Preferably the parts are so formed that the assembled frame is tapered, being somewhat smaller at the end to which the hair is applied.

The lower end of the frame part 2 is merely rounded off with the curved edge 9, but the lower end of the frame part 3, is formed with a hook 11, positioned as shown on each lower corner, while the material between these corners is flared outwardly 90 as shown at 12, and provided with a notch 13.

The hooked portions 11 as shown in Figure 4, are also flared outwardly a small amount to facilitate the engagement of the hair with them, and prevent its injury.

Means are provided for expanding the frame parts to stretch the hair wound thereon. A rod 14 is upset at one end to provide a cone-like plug 16 complementary in shape to the end of the frame parts. At the upper end of the rod, threads 17 are formed, and when the rod is inserted in the frame the application of the thumb nut 18, on the threaded end, serves to draw the coned end 16 into the lower end of the frame and expand it.

It will be observed that the lower end of the frame is of slightly smaller diameter than the opposite end. It will also be observed that the heaviest portion of the hair strand is

wound on the lower end of the frame. Obviously too, the expansion of the frame is greater at the lower end. These three elements work out together to provide a relatively even expansion over the whole strand of hair, since the individual hairs in the heavier portion of the strand, are not subjected to the direct pressure of the expanding frame in the same degree, that the hairs in the thinner portion of the strand are subjected to. That is to say, the hairs in the heavier portion of the strand, mutually cushion and protect each other whereas the hairs in the thinner portion of the strand come into more direct contact with the frame.

The expanding rod may be drawn into the frame by turning the nut 18, which is provided with a boss 19 for centering it in the end of the frame, thus spreading the frame parts to the extent desired. Upon the release of the thumb-nut, the expanding rod slips downwardly to permit the closing of the frame part.

In using my device, the parts are assembled as shown in Figure 2, the expanding rod being loose in the frame. A strand of hair 21 is then combed out to straighten it, and have the individual hairs thereof, lying loosely together without tangle. A string or cord 22 is then wound about the strand close to the scalp and the ends passed thru the slot 13 in the end of the frame 3. One end of the string is passed in one direction around the outside of the frame and across on the inner side and again thru the slot, and the other end is wound in the same way in the opposite direction. With the lower end of the device held close to the scalp, the strand 21 is caught behind the hook 11 on one side, and wound about the closed frame as shown in Figure 2. The loose end 23 of the strand is conveniently secured by a string 24.

The slot 13 in the end of the frame part 3, is of such a size as to hold the string by its wedge action, and upon the turning of the nut 18 to draw in the expanding rod 14, the cone-like portion 16 of the rod engages and still further secures by clamp action the string 22 on the inner side of the frame and at the same time spreads the frame parts, with the effect already explained. The string 22 is for the purpose of securing the strand of hair to the device, so that there

will be less pull on the hair itself tending to unwind it from the frame.

After the hair is applied to the frame, and the frame expanded, the whole is slipped into the electric heating housing 26 of known construction, and which is supplied with current from any suitable source thru the conductor 27. The heating is then continued for from five to twenty minutes according to circumstances, until the desired effect is obtained.

I claim:

1. A hair curling device comprising a longitudinally split tapered frame on which the hair may be wound, means for resiliently retaining the frame sections together, and means for spreading the frame sections to stretch the hair. 70

2. A hair curling device comprising a longitudinally split multiple-part-tapered tubular frame on which the hair may be wound, means for resiliently retaining the frame parts together, an expanding rod within the frame, and means for moving the rod to expand the frame. 75

3. A hair curling device comprising a multiple-part frame on which the hairs may be wound; a spring surrounding one end of the frame to hold the parts together, and means arranged within the frame for spreading apart the other end of the frame to stretch the hair thereon. 80

4. A hair curling device comprising a longitudinally split two-part tapered frame on which the hair may be wound, one of the parts having a hook adjacent the small end of the frame to retain the hair on the frame, means for expanding the frame operative on the small end thereof, and a spring surrounding the large end of the frame to hold the parts together. 85

5. A hair curling device comprising a longitudinally split two-part tapered frame on which the hair may be wound; one of the parts having a hook adjacent the small end of the frame to retain the hair on the frame, a rod within the frame and having a tapered plug thereon disposed within the small end of the frame, means for moving the rod to expand the frame, and a spring surrounding the large end of the frame to hold the parts together. 95

In testimony whereof, I have hereunto set my hand.

MAURICE BOXER.
